(57) **CLAIM**

The ornamental design for a dual chamber tank, as shown and described.

DESCRIPTION

FIG. 1 is a perspective view of a dual chamber tank showing my new design;

FIG. 2 is an elevation view of the design of FIG. 1, wherein all sides of the design are identical;

FIG. 3 is a top plan view of the design of FIG. 1;

FIG. 4 is a bottom plan view of the design of FIG. 1; and, FIG. 5 is an exploded perspective view of the design of FIG. 1.

The broken lines in the drawings depict portions of the dual chamber tank that form no part of the claimed design.
